CLAIM

I claim the ornamental design for a link for a conveyor system, as shown and described.

DESCRIPTION

FIG. 1 is a perspective view from the top, front, and right side of a link for a conveyor system showing the new design.

FIG. 2 is a right side view thereof.

FIG. 3 is a left side view thereof.

FIG. 4 is a rear view thereof.

FIG. 5 is a front view thereof.

FIG. 6 is a top view thereof.

FIG. 7 is a bottom view thereof.

FIG. 8 is a cross-sectional view thereof, taken along the line

FIG. 8-FIG. 8 of FIG. 6; and,

FIG. 9 is a cross-sectional view thereof, taken along the line

FIG. 9-FIG. 9 of FIG. 6.
